(57) CLAIM

The ornamental design for an ultrapure water quality point of delivery unit, as shown.

DESCRIPTION

The unit delivering ultrapure water at the point of use, which includes a support and a dispenser, is a remote, stand-alone dispenser for use with a water purification system.

FIG. 1 is a first perspective view of the ultrapure water quality point of delivery unit;

FIG. 2 is a second perspective view of, the ultrapure water quality point of delivery unit;

FIG. 3 is a front view of the ultrapure water quality point of delivery unit;

FIG. 4 is a rear view of the ultrapure water quality point of delivery unit;

FIG. 5 is a first side view of the ultrapure water quality point of delivery unit;

FIG. 6 is a second side view of the ultrapure water quality point of delivery unit;

FIG. 7 is a top view of the ultrapure water quality point of delivery unit; and,

FIG. 8 is a bottom view of the ultrapure water quality point of delivery unit.
